UNITED STATES PATENT OFFICE.

PERCY HAMILTON HANCOCK, OF THORNTON HEATH, ENGLAND, ASSIGNOR TO THE SUPERHEATER COMPANY, OF NEW YORK, N. Y.

STEAM SUPERHEATER OF THE MULTIPLE SMOKE OR FIRE TUBE TYPE.

Application filed November 23, 1925, Serial No. 70,810, and in Great Britain June 13, 1924.

This invention relates to steam superheaters of the smoke or fire tube type in which the steam superheating pipes or superheater elements comprise U-loop portions or pipes which extend into the smoke or fire tubes of the boiler and each element has its saturated steam inlet end and superheated steam outlet end connected to a header or headers in the smoke box or uptake of the boiler either above or to one side of the group or nest of smoke or fire tubes into which the U-pipes of the elements extend. The present invention has been primarily designed for application to marine boilers of the smoke or fire tube type such as for instance the well known Scotch marine boilers, but the invention is not necessarily restricted to marine boilers.

The present invention has for its principal object to provide a steam superheater of the type above mentioned which possesses or provides several important practical advantages as compared with steam superheaters of the smoke or fire tube type as heretofore fitted to marine or similar boilers. For instance a superheater according to this invention is not only cheaper to construct, install and maintain than existing superheaters as fitted to marine boilers, but also provides greater facilities for disconnecting the elements and withdrawing them from the boiler smoke tubes when necessary to do so, the construction and arrangements being such that every element appertaining to a nest or group of the boiler smoke tubes can be individually or independently and easily disconnected from the header or headers and withdrawn from the smoke tube or tubes to which it appertains without removing or disturbing any other element appertaining to the group or nest of smoke tubes and without the necessity of special and complicated bending of the saturated steam inlet and superheated steam outlet end portions of the element which lie or extend within the uptake or smokebox of the boiler. Further the fastening nuts of the studs or bolts by which the elements are coupled or secured to the saturated and superheated steam headers (or it may be to a single

header having a saturated and a superheated steam chamber as is usual) are more easily accessible for the purpose of fitting up and disconnecting the elements than in existing superheaters of the type to which the present invention relates. Further, all the superheater elements appertaining to a group or nest, or it may be to two or more groups or nests, of the boiler smoke tubes may be uniform (or substantially so) one with another so that all or nearly all of the elements which have the same number of U-pipes are interchangeable. Further each element, removable from its smoke tubes individually and independently of the removal of every other element, as above mentioned, can be readily withdrawn from its smoke tubes by a simple straight forward movement of the element within the lines of the group of smoke tubes into which it extends.

The present invention principally consists in a steam superheater of the type above specified in which superheater elements appertaining to a row or adjacent rows of smoke tubes have their saturated steam inlet and superheated steam outlet ends connected to a plurality of members, one for each element, having steam passages therethrough which lie transversely of the longitudinal centre lines of the said smoke tubes the said members being arranged with the respective steam passages in line and being detachably secured to one another and to the header. The said header is as usual fitted in the uptake or smokebox of the boiler, and in the case of a superheater for a marine boiler the header or headers would, as usual, be arranged vertically in the uptake and opposite the spaces between the several nests of the boiler smoke tubes appertaining to the several furnaces of the boiler.

The above-mentioned members to which the ends of the elements are connected are provided at each end with means for coupling them together, or to the header, with their steam passages in line, such means comprising, for instance flanges and bolts or other fastening devices, and the members are of such a length that when those belonging to the elements appertaining to a row

or rows of smoke tubes are coupled together and to the header each member lies opposite the group or series of smoke tubes to which its element appertains, the construction and arrangement being such that any member may be disconnected from the remaining members and from the header and, together with the element to which such disconnected member appertains, be removed from the boiler without disturbing any other element or breaking any joints other than those at the opposite ends of the said disconnected member.

Further according to this invention, in an embodiment for application to a marine boiler of the multiple smoke or fire-tube type, the saturated steam inlet end and superheated steam outlet end of each of the elements appertaining to smoke tubes in each 20 horizontal row or in each of two adjacent horizontal rows are connected with (for instance welded to) two transversely arranged and preferably parallel pipes or tubes on the opposite ends of which tubes are provided 25 plates or flanges in which the ends of the said transverse pipes are fixed (for instance expanded), the end portions of each element, extending from the boiler smoke tubes to the said transverse pipes being plain straight 30 ends without any bend between the boiler tube plate and the said transverse tubes, with the possible exception of a slight bending of the outer ends for attaching same to the transverse tubes. For fitting up or coupling together the ends of the several elements appertaining to the same horizontal 35 row or rows of smoke tubes the above mentioned flanges or plates on the transversely arranged tubes of adjacent elements are 40 brought together in a vertical plane and secured together by means of studs or bolts and nuts. The plate or flange on the transversely arranged tubes of the element which occupies the smoke tubes nearest the hereinbefore mentioned vertically arranged main 45 header or headers may be secured to the said header or headers by the flange or plate on the ends of said transverse pipes adjacent to the header being secured by studs or bolts 50 and nuts either directly to suitable faces on the side of the header or headers or to flanges or plates on the outer ends of short tubular projections on the side or sides of the header or headers. The construction and 55 arrangements are such that the fastening nuts for securing together the flanges or plates appertaining to the ends of adjacent elements in the horizontal row or rows of smoke tubes are very easily accessible.

60 The accompanying drawings illustrate, by way of example, a steam superheater for a marine boiler of the multiple smoke or fire tube type. In the drawings,—

65 Fig. 1 is an elevation of a portion of a marine boiler showing the boiler tube plate

at uptake end of the boiler, and illustrates one half of a superheater according to the present invention.

Fig. 2 is a plan view, partly in section, of

70 Figs. 3 and 4 are respectively a sectional elevation and a plan of a portion of the boiler and one of the superheater elements, drawn to a larger scale than that of Figs. 1 and 2.

75 Figs. 5 and 6 are, respectively, a side elevation and a plan of the main headers of the superheater illustrated in Figs. 1 and 2.

80 Like reference numbers indicate corresponding parts in the several figures of the drawings.

Referring to Figs. 1 and 2 of the drawings, 1 is the boiler tube plate at the smoke box or uptake end of the boiler, and 2 are the boiler smoke tubes arranged, as usual, 85 in groups or nests appertaining to the respective furnaces of the boiler.

90 3 are the main headers of the superheater arranged vertically in the uptake of the boiler; these headers will be hereinafter more 95 fully described.

95 As shown in Figs. 1 and 2 there is a plurality of superheater elements having **U**-loops or **U**-pipes extending into smoke tubes 2 in each of two adjacent lateral or horizontal rows of the smoke tubes, and each of the superheater elements appertaining to the smoke tubes in the said rows has a number of **U**-loops extending into a corresponding number of smoke tubes in the said rows, 100 these being known arrangements.

105 As hereinbefore mentioned the saturated steam inlet and superheated steam outlet ends or end portions respectively 4, 4^a of each of the superheater elements are connected with a tubular member arranged transversely or at right angles to the said ends or end portions 4, 4^a of the element, the said tubular members in the embodiment illustrated in the drawings consisting of two lengths of 110 pipe or tube 5 and 5^a arranged side by side, the ends of these pipes being secured, for instance expanded, in holes in plates or flanges 6 and 6^a, the end of the saturated steam inlet pipe 4 of each element being secured, for instance welded, in registration with a hole or port in the tube 5 and the superheated steam outlet end 4^a of the element being similarly secured to the pipe or tube 5^a. As will be seen on reference to Figs. 1 and 2 the end portions 4 and 4^a of each superheater element are plain straight portions with the exception of a slight bending of these pipes for attaching same to the transverse tubes 5 and 5^a, this slight bending being indicated at 7. As shown in Figs. 1 and 2, for fitting up or coupling together 125 the ends of the several superheater elements belonging to the same horizontal row or rows of smoke tubes the flanges or plates 130

125 130

6, 6^a, of the adjacent transverse tubular members comprising the tubes 5 and 5^a, are brought together in a vertical plane and secured together by means of bolts and nuts, for instance as illustrated in Figure 4 of the drawings.

The flange or plate 6 of the transverse tubular member of the superheater element appertaining to the smoke tubes nearest the main or vertical header 3 is secured by bolts and nuts to a corresponding flange or plate 8 provided on the outer ends of two short tubular connections or projections 9, 9^a on the side of the main or vertical header 3, the tubular connection 9 making communication with the saturated steam chamber of the header and the tubular connection 9^a making communication with the superheated steam chamber of the header. As will be seen the construction and arrangements are such that the fastening nuts for securing the flanges or plates 6 and 6^a appertaining to the transverse tubular members of adjacent superheater elements in the horizontal row or rows of smoke tubes are very easily accessible for manipulation both for tightening up and thus securing the several elements in the row or rows of smoke tubes together and for disconnecting the said elements should it be necessary to withdraw one or more of the elements.

It will be understood that each of the pipes or tubes 5 and 5^a of the hereinbefore mentioned transversely arranged tubular members of the superheater elements is of a cross area suitably larger than the cross area of the pipe (4 and 4^a respectively) connected to it.

In the construction thus far described it will be understood that each of the U-loop superheater elements as a unit comprises the transversely arranged tubular members consisting, in the embodiment illustrated, of the lengths of pipe or tube 5 and 5^a having on their opposite ends a flange or plate common to the adjacent ends of the two said pipes 5 and 5^a, the said flanges or plates 6 and 6^a serving for coupling together the several superheater elements having U-loops appertaining to a horizontal row or rows of the boiler smoke tubes.

In Fig. 3, 10 are holes through the flange or plate 6^a of the transversely arranged tubular member of a superheater element, a similar arrangement of the bolt holes being provided in the flanges or plates 6, 11, Fig. 4, indicates the bolts with their nuts 12.

As shown in Figs. 1 and 2 certain of the superheater elements, i. e. the elements in the boiler smoke tubes situated farthest from the vertical or main headers 3, are of a known form in which the end portions of the elements within the boiler uptake are bent laterally towards the said vertical or main header 3 the saturated steam inlet and

superheated steam outlet ends of each of these elements being secured in a plate or flange 6^b, Figs. 1 and 2, similar to the above mentioned plates or flanges 6 and 6^a, the said flanges or plate 6^b being secured to the adjacent flange or plate 6^a, appertaining to the adjacent element in the row, by bolts and nuts as in the case of the flange plates 6 and 6^a.

The superheater elements appertaining to the boiler smoke tubes in the intermediate or centre nest of such tubes may be of somewhat different form or construction from those above described. For instance the superheater elements belonging to the centre nest of boiler smoke tubes may be arranged as shown in Figs. 1 and 2 in which the flanges or plates 6^c are provided on the laterally bent ends of these elements and the said flanges or plates are secured by bolts and nuts to the flanges or plates 8 of the short tubular connections to the vertical header 3.

In the preferred embodiment according to this invention the main headers 3, comprising as usual a saturated steam chamber or header and a superheated steam chamber or header preferably arranged one behind the other, consist of lengths of simple standard steam tube of suitable diameter or cross area in the side or in opposite sides of which tubes openings 13 and 14 of suitable diameter or cross area are provided the openings 13 communicating with the saturated steam chamber of the header and the openings 14 communicating with the superheated steam chamber of the header. In these openings the hereinbefore mentioned short pieces of tube 9, 9^a are secured, for instance welded, the outer ends of these short tubes being secured in holes in the hereinbefore mentioned flanges 8 for instance by being expanded in the said flanges.

The two pieces of tube which constitute the main header 3 with its saturated and superheated steam chambers are preferably secured together the one behind the other by means of split collars or clamps 15 between the flanges 15^a of which may be secured the plates or brackets 16, 16^a whereby the main header is secured in position within the boiler uptake, the bracket or plate 16^a being secured to the boiler tube plate 1 and the bracket or plate 16 secured to a suitable part of or connected with the structure of the uptake. The plates 16 and 16^a may be secured between the flanges 15^a of the clamps 15 by rivets or bolts and nuts which serve to secure the parts together. If desired the collars or clamps 15 may also be welded to the tubes forming the header. Each of the tubes forming the header in the embodiment illustrated is closed at its lower end by a cap or plate 17 which may be welded to the tubes, and at

the upper or open ends of the said tubes flanges 18 are provided, (for instance welded to the upper end of the tubes), for connection with the usual saturated steam pipe line from the boiler and with the usual or appropriate superheated steam pipe line or connection to the engine. As clearly shown in Figs. 5 and 6 the upper ends of each of the pieces of standard steam tube 3^a and 3^b 10 are bent or set near their upper ends so that these upper end portions are separated by a space sufficient to accommodate the flanges 18.

The hereinbefore mentioned tubular members comprising the transversely or horizontally arranged tubes 5 and 5^a associated with or forming part of each superheater element or unit are preferably so arranged that the said tubes 5 and 5^a lie in the plane 15 between the adjacent rows of smoke tubes to which the elements appertain.

If desired the end portions or pipes 4, 4^a 20 of the superheater elements, i. e. the portions which extend into the uptake or smoke-box of the boiler, may be secured in the respective transverse pipes or tubes 5 and 5^a 25 by being expanded in holes therein in any known or suitable manner.

If desired supporting means, for instance 30 lugs or brackets, which might be secured to the boiler tube plate 1 at the uptake or smoke box end of the boiler or to the plates forming the walls or shell of the uptake, may be provided for supporting the hereinbefore mentioned transverse tubes to 35 which the ends of the superheater elements are secured.

In an alternative embodiment of the invention, suitable for application to a locomotive boiler, instead of the tubes 5, 5^a with 40 end flange connections 6, 6^a and to which tubes the saturated steam inlet and outlet end portions 4, 4^a of the several superheater elements are secured being arranged transversely or horizontally as hereinbefore described and shown in the drawings, the said tubes 5, 5^a may be arranged vertically, and the uppermost tubes 5, 5^a appertaining to the 45 several elements in a row or rows (it may be a vertical row or rows) of the boiler smoke tubes may be secured by the flange on the upper ends of said tubes 5, 5^a to a flange or flanges on the main header which in this 50 case may be arranged horizontally in the upper part of the smoke box above the group of boiler smoke tubes into which the superheater elements extend.

Although in the drawings, Fig. 1, an arrangement of the superheater elements is 60 shown in which each element has a number of U-loops extending into a corresponding number of smoke tubes in two adjacent rows of smoke tubes, the invention is not restricted to this arrangement as elements 65 which have a number of U-loops extending

into the smoke tubes in only one row of smoke tubes might be employed.

The faces of the hereinbefore mentioned flanges or plates 6 and 6^a on the transverse tubular members on or connected with the 70 saturated steam inlet and superheated steam outlet ends of the superheater elements may be machined true so as to provide effective steam tight jointing of the adjacent flanges 6 and 6^a appertaining to the adjacent elements; if desired, however, a suitable joint-making material might be provided between the adjacent faces of the said flanges 6 and 6^a. Similar provision would of course be 75 made for the jointing of the flanges 6 of the elements situated nearest the main header 3 to the flanges 8 on the short projecting tubes 9 and 9^a on the header.

What I claim is:—

1. In apparatus of the class described, the 85 combination of a flue sheet; a plurality of parallel smoke-tubes secured to said sheet; a bi-chambered subsidiary header comprising a plurality of bi-chambered sections 90 separably secured to each other end to end, each section obstructing access to a plurality of smoke-tubes; a plurality of tubular superheater elements the ends of each element being secured respectively to the two chambers of a section, each element extending into smoke-tubes obstructed by its 95 section and lying entirely outside of all smoke-tubes obstructed by other sections than the one to which it is secured; whereby each section and its attached element can 100 be removed without disturbing any other section.

2. In apparatus of the class described, the 105 combination of a flue-sheet; a plurality of parallel smoke-tubes secured to said sheet; a subsidiary bi-chambered header comprising a plurality of sections; each section composed of two parallel tube lengths whose 110 ends are secured into common flanges; said sections being separably secured to each other by means of said flanges; each section obstructing access to a plurality of smoke-tubes; a tubular superheater element secured to each section, one end to each tube 115 length, and extending into smoke-tubes obstructed by such section; each element lying entirely outside of all smoke-tubes obstructed by other sections than the one to which it is secured; whereby each section and its attached element can be removed 120 without disturbing any other section.

3. In apparatus of the class described, the 125 combination of a flue-sheet; a plurality of parallel smoke-tubes secured to said flue-sheet; a main bi-chambered superheater header parallel to the flue-sheet and out of line with the smoke-tubes; a plurality of subsidiary bi-chambered headers secured to said main header, each comprising a plurality of sections, each section composed of 130

two parallel tube lengths arranged in a plane perpendicular to the flue-sheet with their ends secured into common flanges; each section obstructing access to a plurality of smoke-tubes; a tubular superheater element secured to each section, one end to each tube length, and extending into smoke-tubes obstructed by such section; each element lying entirely outside of all smoke-tubes ob-

structed by other sections than the one to which it is secured; whereby each section and its attached element can be removed without disturbing any other section or the main header.

In testimony whereof I affix my signature.

PERCY HAMILTON HANCOCK.
